Primary Examiner — Elizabeth J Oswecki(74) *Attorney, Agent, or Firm* — Clause Eight IPS; Michael Catania(57) **CLAIM**

The ornamental design for a muddle, as shown and described.

DESCRIPTION

FIG. 1 is a top perspective view of a muddle showing a bottle opener at one end showing our new design.

FIG. 2 is a top plan view thereof.

FIG. 3 is a bottom plan view thereof illustrating an opening of the muddle.

FIG. 4 is a side view thereof.

FIG. 5 is a bottom perspective view thereof; and,

FIG. 6 is a cross-sectional view taken along line 6-6 of FIG. 1. All sides not shown form no part of the claimed design. In the drawings, the broken lines in FIGS. 1-6 depict portions of the design that form no part of the claim.
